UNITED STATES PATENT OFFICE.

SEYMOUR E. HOTCHKISS, OF WALLINGFORD, CONNECTICUT.

DESIGN FOR A DELIVERY-SPOUT.

SPECIFICATION forming part of Design No. 25,415, dated April 21, 1896.

Application filed January 8, 1896. Serial No. 574,752. Term of patent 14 years.

To all whom it may concern:

Be it known that I, SEYMOUR E. HOTCHKISS, a citizen of the United States, residing at Wallingford, in the county of New Haven and State of Connecticut, have invented and produced a new and original Design for a Delivery-Spout, of which the following is a specification, reference being had to the accompanying drawing, forming part thereof, in which the only figure is a perspective view of a delivery-spout, showing my design.

The rectangular body is divided at its effluent end into two rectangular and divergent arms.

15 A designates the body of the spout of a rectangular form in cross-section, its width being materially in excess of its height.

B B designate the delivery-arms, which at their junction with the body A form in cross-

section a rectangular figure of half the dimension of said body, while said arms are flattened toward their delivery ends *aa*, being gradually narrowed vertically and widened laterally, as shown, so that the sum of the four sides at the open delivery ends *a* is practically the same as at their junction, and consequently both of said arms have substantially the same area in cross-section throughout their length, although their relative depth and width varies gradually from end to end. Said arms also diverge outwardly, as shown.

What I claim is—

The design for a delivery-spout substantially as shown and described.

SEYMOUR E. HOTCHKISS.
